UNITED STATES PATENT OFFICE.

GRANT E. HOOVER, OF FREEPORT, ILLINOIS.

CLOTHESLINE POLE.

Application filed April 27, 1922. Serial No. 556,928.

To all whom it may concern:

Be it known that I, GRANT E. HOOVER, a citizen of the United States, residing at Freeport, in the county of Stephenson and 5 State of Illinois, have invented certain new and useful Improvements in Clothesline Poles, of which the following is a specification.

This invention pertaining in general to 10 laundry apparatus, has more particular reference to clothesline poles adapted for supporting a clothesline at an intermediate point to prevent sagging under weight of the clothes.

15 The primary object of the invention is to provide an improved clothes pole which is extensible so that the line may be supported at different elevations and which is equipped with novel means for engaging the clothesline for preventing displacement of the pole from its set position.

I have also aimed to provide a clothesline pole of the character described which may be quickly and easily applied and removed 20 from its operative position.

25 Another object is to provide a clothesline pole embodying the novel features described, constructed in such simple manner as to be capable of economical production.

30 Other objects and attendant advantages will be appreciated by those familiar with this art as the invention becomes better understood by reference to the following description when considered in connection with 35 the accompanying drawings, in which—

Figures 1 and 2 are face and side views, respectively, of a clothesline pole embodying my invention;

Fig. 3 is an enlarged face view of the upper end of the pole as taken on the section line 3—3 of Fig. 2;

Fig. 4 is a sectional view taken on the line 4—4 of Fig. 3; and

Fig. 5 is a detail view of the rope clamp.

45 Referring more particularly to the drawing, it will be observed my improved pole is of sectional construction comprising a base section 6 and an extensible section 7 slidably associated and held together by guide straps 8 and 9 fixed to the pole sections 6 and 7, respectively. The base section 6 has an anchor pin 11 for maintaining location in the ground and the extensible section 7 carries a spring-pressed detent or plunger 12 adapted to engage in any of the holes 13 in the 50 section 6 for securing the pole section 7 in

any extended position. The pin 12 may be withdrawn by grasping the knob or handle 14 at its outer end. A suitable sheet metal casing 15 houses the plunger spring and provides a guide for the plunger.

60 My invention also contemplates the provision of a locating element adapted to be clamped at any desired point on the clothesline, and the provision of a specially constructed end on the extensible section of the pole for operative engagement with said locating element. This locating element in its preferred embodiment is in the form of 65 a longitudinally split sleeve 16 having enlarged ends 17 and formed of flexible material, such for example as lead or any suitable composition. The sleeve when in the separated condition shown in Fig. 5, may be slipped over a clothesline 18 and then closed 70 so as to be tightly clamped thereon and held against shifting in either direction. The end of the pole section 7 is slotted to provide a transverse socket 19 having a tapered mouth 21 converging toward the socket. A 75 longitudinal slot 22 in the end of the pole section 7 intersects the socket 19, allowing the separated ends of the pole to be sprung apart. A corrugated sheet metal insert 23 pressed into each face of this pole section at 80 the base of the slot 22 serves to prevent the pole from splitting. The sleeve 16 is adapted to seat in the socket 19, and the outer diameter of said sleeve is greater than the width of said socket. Consequently, when 85 inserting the sleeve 16, it will engage the tapered sides 21 and slightly spread the separated ends of the pole section so that the sleeve will be entered into the socket 19 under sufficient pressure and frictional 90 resistance as to hold the sleeve in the socket. The ends 17 of the sleeve engage the side faces of the pole section and thereby prevent endwise displacement of the sleeve from the pole section. In this manner the 95 pole will be so connected with the clothesline as to positively prevent accidental displacement, and at the same time the pole may be easily removed at will, by the attendant. The clamp forms a permanent pole-locating means, although if desired, it may 100 be easily loosened and secured at a different location on the clothesline.

105 By the use of a clothesline pole of the character described, there will be little or no danger of the line blowing down if the pole is properly adjusted as to height. This 110

result is obtained by reason of the lower end of the pole being anchored to the ground, the extensibility of the pole to secure the desired elevation, and the fixed connection 5 of the pole at its upper end to the clothesline. This positioning and connection of the pole may be quickly and easily effected, as will be obvious and the pole may be removed with equal facility.

10 It is believed that the foregoing conveys a clear understanding of the objects preferred above, and while I have illustrated but a single working embodiment it should be understood that changes might be made 15 in details of construction without departing from the spirit and scope of the invention as expressed in the appended claims.

I claim:

1. The combination with a clothesline, of 20 a longitudinally split sleeve adapted to be clamped onto the line, and a line-supporting pole having means adapted to detachably

interfit with said element for holding the upper end of the pole in connection with the line. 25

2. The combination with a clothesline, of a locating element formed of yielding material and adapted to be clamped to said line, and a line-supporting pole having at its upper end a tapered mouth socket intersected by a longitudinal slot, said element adapted to be pressed into said socket against the pressure of the yieldable sides thereof. 30

3. A clothesline support comprising a pole 35 having a socket in its upper end and a longitudinal slot intersecting said socket, and a sleeve of yieldable material adapted to embrace and be clamped to the clothesline and having end collars, said sleeve adapted to seat in said socket with the pole interposed 40 between said collars. 40

GRANT E. HOOVER.
